UNITED STATES PATENT OFFICE.

ARIETTE BAIRD, OF RIVERHEAD, NEW YORK.

COMBINED BABY TENDER AND CRIB.

SPECIFICATION forming part of Letters Patent No. 485,081, dated October 25, 1892.

Application filed March 15, 1892, Serial No. 424,977. (No model.)

To all whom it may concern:

Be it known that I, ARIETTE BAIRD, residing at Riverhead, in the county of Suffolk and State of New York, have invented a new and 5 Improved Combined Baby Tender and Crib, of which the following is a specification.

My invention is designed to provide a neat, simple, practical, and sanitary device, which may be used alternately as a baby tender or 10 crib, in which an infant or child of tender years may be placed and kept amused and out of danger and free from the necessity of the constant watchfulness and care of its mother, or which device by slight adjustment 15 may be converted to the use of a crib, in which the child may be safely and comfortably placed while it sleeps. In my prior patent, granted me May 25, 1875, No. 163,625, I have aimed at and attained some of these results. 20 My present invention is an improvement upon that construction; and it consists in the peculiar construction and arrangement of parts, as will be hereinafter fully described.

Figure 1 is a perspective view of the device 25 detached into its two parts for folding, and Figs. 2 and 3 are respectively a side elevation and a transverse vertical section of the device as adjusted for use as a crib.

In the drawings, A A' represent the two 30 sides, and B B' the two ends, of the combined baby tender and crib. These sides and ends are each made alike, except that the sides are longer. They consist simply of a rectangular frame a a a a and vertical parallel slats or 35 bars b, inserted in the horizontal members of the rectangular frame or otherwise attached to the same. Each side panel has rigidly attached to its ends the vertical corner-posts C C, which are rigidly fastened thereto. To one 40 of these posts on each side panel is hinged at c c an end panel, and the other post of the same side panel has in its face two plates with keyhole-slots d d, which are adapted to receive the hook-shaped fastenings e e on the edge of 45 the adjacent end panel of the other half of the frame, said fastenings being in the nature of bedstead-fastenings, whose construction is well known, and in the place of which any similar detachable fastening may be employed. 50 From this description it will be seen that the main frame has hinges at one pair of its diag-

onal corners and separable joints at the other pair of its diagonal corners, so that the main frame separates in two halves, consisting each of a side panel and an end panel, which are 55 hinged together and adapted to fold flat, the one against the other. By this construction it will be seen that the main frame may be folded perfectly flat and be very conveniently carried from room to room or up and down 60 stairs even by a child. Furthermore, the method of constructing the panels of a rectangular marginal frame with only vertical parallel bars prevents the child from finding 65 a foothold for climbing out, as would be afforded by horizontal bars or rails, as in my first patent.

In the bottom of the framework and distended and secured by eyelets at its edges engaging with hooks or buttons on the lower 70 edge of the frame is a floor-covering F, substantially as shown in my prior patent. This may be in the nature of a carpet or rug for warmth, or it may be a gum-cloth to prevent the child from wetting the floor or soiling it 75 with its food or drink or otherwise. This floor-covering also serves the purpose of preventing the child from overturning the main frame, the child's weight being on this floor-cloth, which thus holds the frame down, and 80 said floor-cloth, being under some tension, also holds the separable halves of the main frame from coming apart, and thus exercises a coactive function with this detachable construction of frame. 85

E is the hammock, which is slung from the top rails of the main-frame panels by means of elastic straps f, which pass through loops g, attached to the hammock at a reinforced seam just below its upper edge. This seam 90 is shown at s in Fig. 3, and the object of this means of attachment is to place the straps and fastening devices out of the reach of the child, and also to leave the upper edge of the hammock free from all metallic projections 95 which might injure the child in its movements. The two ends of these elastic straps are each provided with fastening-loops h and i, the one h a plain metal loop and the other i a bent or hook-shaped metal loop that is hooked into 100 the first outside the top bar of the panels, so as to embrace the same and form a point of

- attachment to support the hammock. These elastic straps with loops are arranged at short intervals along both the sides and ends and form a simple and easily-adjusted means of attachment. The hammock E itself is made of any sort of strong woolen or cotton cloth and has semi-elliptical ends E', with a stiffening-bow m, of wire, wood, or other material, distending the lower portion and sides of said ends, the said bow being incorporated in a seam of the material. This holds the hammock straight and prevents it from doubling up about the child and rendering it uncomfortable.
- 15 When used as a baby-tender, a cushion or seat may be placed inside the same, and when used as a crib a canopy of mosquito-netting may be arranged to cover the same to keep away flies and other insects.
- 20 At suitable points along the top rail are fastened screw eyes or loops for securing by

a flexible cord or ribbon a teething-ring r, rattle, or other plaything for amusing the child.

Having thus described my invention, what I claim, and desire to secure by Letters Patent, is—

The combined baby tender and crib consisting of the two detachable and folding frame-sections A B and A' B', the hammock consisting of the flexible bottom part E and flexible end sections E', the curved stiffening-bow m, arranged in the hem or seam between the bottom and end sections, and the straps f, with fastenings and loops g, connected to a seam s of the hammock on its outer side and below its upper edge, substantially as and for the purpose described. 30 35

ARIETTE BAIRD.
